CLAIM

The ornamental design for intake nozzle for cutting machine's combustion motor, as shown.

DESCRIPTION

FIG. 1 shows the intake nozzle for a cutting machine's combustion motor in a perspective view;

FIG. 2 shows the nozzle in a perspective view in the opposite direction;

FIG. 3 is a top perspective view of the nozzle;

FIG. 4 is a bottom perspective view of the nozzle;

FIG. 5 shows a front side of the nozzle;

FIG. 6 shows the rear side of the nozzle;

FIG. 7 is a side elevation of the nozzle; and,

FIG. 8 is a side elevation of the nozzle in the opposite direction.
